(57) **CLAIM**

The ornamental design for a baking rack, as shown and described.

DESCRIPTION

FIG. 1 is front perspective view of a baking rack;

FIG. 2 is a rear perspective view thereof;

FIG. 3 is a front view thereof;

FIG. 4 is a rear view thereof;

FIG. 5 is a right side view thereof; and

FIG. 6 is a left side view thereof;

FIG. 7 is a top view thereof;

FIG. 8 is a bottom view thereof;

FIG. 9 is a first perspective view thereof with environmental elements illustrated in broken lines; and,

FIG. 10 is a second perspective view thereof with environmental elements illustrated in broken lines.

The broken lines are included for the purpose of illustrating environmental elements only and form no part of the claimed design.
